UNITED STATES PATENT OFFICE.

HENRY O. NIELSEN, OF ELKO, NEVADA.

PERMUTATION-PADLOCK.

1,257,013.

Specification of Letters Patent. Patented Feb. 19, 1918.

Application filed July 28, 1917. Serial No. 183,248.

To all whom it may concern:

Be it known that I, HENRY O. NIELSEN, a citizen of the United States, residing at Elko, in the county of Elko, State of Nevada, have 5 invented certain new and useful Improvements in Permutation-Padlocks; and I do hereby declare the following to be a full, clear, and exact description of the invention, such as will enable others skilled in the art to 10 which it appertains to make and use the same.

This invention is an improvement in locks and has particular reference to a permutation pad lock.

15 An object of the invention is to provide improved means for locking the parts of the lock together in such manner that the same may be separated only when said means is in its unlocking position.

20 Another object is the provision of a detent of novel construction carried by one of the shackles of the lock so that the same may be adjusted by the other shackle to an unlocking position to permit of an operation of the 25 parts of the lock.

A further object is to provide a lock of this character which is simple in construction, easy to manufacture and effective in carrying out the purpose for which it is designed.

30 The inventive idea involved is capable of receiving a variety of mechanical expressions, one of which, for the purpose of illustrating the invention, is shown in the accompanying drawing, wherein:—

Figure 1 is a side elevation of the lock constructed in accordance with the invention.

Fig. 2 is an enlarged fragmentary section with the parts in locking position.

40 Fig. 3 is a similar view with the parts in unlocked position.

Fig. 4 is a transverse section on the line 4—4 of Fig. 2.

Fig. 5 is a perspective view of the detent 45 and locking bar employed.

Fig. 6 is a similar view of one of the tumblers.

The lock preferably comprises a pair of shackles 10 and 11, the latter having an enlarged end 12 provided with a socket 13 for receiving one end 14 of the shackle 10, said end being reduced as indicated at 15

to provide shoulders 16 for limiting the longitudinal movement of the shackles relative to each other, detachment of the ends 12 55 and 14 being prevented by transverse pins 17 extending across the socket 13 and engaging the reduced portion 15.

The opposite end of the shackle 11 is also enlarged as indicated at 18 and provided 60 with a longitudinal opening 19 for receiving the locking end 20 of the shackle 10, said locking end being provided with a notch 21 for a purpose which will presently appear.

Adjustable in the enlargement 18 and extending longitudinally of the edge of the locking end 20 having the notch 21 therein is the detent 22 preferably in the form of a plate provided at each end thereof with diagonally projecting reduced extensions or 70 pins 23 which engage in suitable recesses in the enlargement 18 so as to guide the detent in its adjustments. These pins 23 are arranged in a diagonal relation with reference to the detent and also the locking end 20 so 75

that said detent, when adjusted, will move in a direction which is diagonal to the longitudinal axis of the enlargement 18 whereby the same may be adjusted toward and away from said locking end 20. The detent is 80 normally retained in its locking position by means of a coil spring 24 engaging one end of the pins or extensions 23 which force the detent toward the end 20. Pivoted to the detent 22 at 25 is a locking pawl 26 the free 85 end of which engages in the notch 21 when in locking position and is retained in said position by means of a leaf spring 27 secured to the detents and having its free end engaging the adjacent longitudinal edge of 90 said bar.

The movement of the pawl 26 toward its locking position is limited by a shoulder 28 formed upon the detent and providing a stop which engages the longitudinal edge of 95 the pawl opposite that engaged by the spring 27.

A plurality of tumblers 29 are rotatably mounted upon the enlargement 18 and each tumbler is provided with a recess 30 which 100 is adapted to be aligned with the recesses of the other tumblers, by a suitable combination, so that the locking end 20 may be extracted from its locking position.

When the recesses 30 are alined a pull upon either of the shackles will cause a diagonal movement of the detent 22 and the locking pawl 26 away from the locking end 20 until the free end of the pawl 26 is disengaged from the notch 21 and when moving in this diagonal direction the outer longitudinal edge of the detent 22 will enter the recesses 30. Upon the disengagement of the pawl 26 from the notch 21 the locking end 20 may be withdrawn from the enlargement 18 whereupon the shackles will be unlocked. As soon as the locking end 20 has been withdrawn past the locking pawl 26 the spring 24 will return the detent and bar to their normal positions and when the locking end is again inserted into the opening 19 the same will initially swing the pawl 26 about its pivot against the tension of the spring 27 after which said pawl will engage in the notch 21 and thus maintain the end 20 in its locking position. The end 20 is provided with an angular shoulder 31 adapted to engage the adjacent end of the enlargement 18 when the parts are in locking position whereby to prevent the insertion of a wire or other implement into

the opening 19 with the end in view of disengaging the pawl 26 from the notch 21.

What is claimed is:—

30 A permutation pad lock including a pair of shackles one end of one of which is provided with an opening, an adjacent end of the other shackle being insertible into said opening and provided with a notch, 35 a detent adjustable in the first named end and having pins extending diagonally from the ends thereof whereby to guide said detent toward and away from said locking end when said detent is adjusted, means 40 normally retaining the detent in its locking position, a locking pawl pivoted to said detent and normally in position to engage the notch in the second named end, and recessed tumblers mounted upon the first 45 named end and adapted to have their recesses alined to receive a portion of said detent when the same is adjusted.

In testimony whereof, I affix my signature in the presence of two witnesses.

HENRY O. NIELSEN.
